UNITED STATES PATENT OFFICE.

LLOYD SYKES, OF ALLIANCE, OHIO.

CURTAIN BRACKET.

Application filed May 19, 1924. Serial No. 714,318.

This invention relates to brackets for use in supporting curtain rods and shades, and the objects of the invention are to provide a one-piece bracket, of simple, ornamental, and rigid construction, which may be readily applied to and secured in the desired position upon a window frame or the like, the bracket being designed to support a straight curtain rod for carrying a lace curtain rod, a bow-end rod for carrying an overdrapé and provided with notches for receiving the pintles of a shade roller.

The above and other objects are attained by constructing the bracket in the manner illustrated in the accompanying drawing, in which—

Figure 1 is a perspective view of a bracket embodying the invention; and

Fig. 2 a plan view of two brackets supporting the rods and shade roller.

Similar numerals refer to similar parts throughout the drawing.

The bracket, as shown in Fig. 1, is preferably formed or stamped from a single sheet or plate of metal, being of substantially S-shape, as shown at 1, and provided with the angular attaching ears 2 at the upper and lower portions of the rear edge thereof, these ears being provided with apertures 3 to receive screws, tacks or the like, as shown at 4.

The horizontal upper edge portion of each bracket is rolled as shown at 5, and is split for a portion of the way from its forward edge, forming the arm 6 which is bent inward at right angles to the normal plane of the bracket, terminating in the angular ear 7 parallel to the attaching stud and having a substantially U-shaped notch 8 in its upper edge.

The rolled portion thus extends outward beyond the arm 6, forming a cylindrical attaching stud 9 adapted to receive the bowed end portions 10 of a rod 11, adapted to carry any suitable kind of overdrapé, while a straight rod 12, adapted to carry a lace curtain, is supported in the notches 8 of the angular ears 7. The lower leg of the S-shaped body portion of each bracket, is provided with a notch 13 extending through its upper

edge to receive the adjacent pindle 14 of a shade roller 15.

In applying the bracket as shown in Fig. 2, one bracket is attached by the nails 4, through the ears 2, to each side of the window frame, the arms 6 being directed toward each other, whereby the rod 12 carrying the lace curtain will be concealed by the bow-end rod 11 carrying the overdrapé.

The shade roller 15 is also concealed by the overdrapé, thus making a very neat one-piece fixture adapted to support the curtain, overdrapé and shade roller.

I claim:—

1. A curtain bracket formed of a single sheet of metal having its forward end slit, the upper edge of the sheet being rolled to form a horizontal attaching stud for a bow-end rod, and the portion beneath said slit being bent laterally away from and at an angle to the attaching stud and provided with a notched angular portion located parallel to the attaching stud to support a straight rod.

2. A curtain bracket of the character described formed of a single sheet of metal having its forward end slit and its upper edge rolled to form a horizontal attaching stud for a bow-end rod, the portion beneath said slit being bent laterally away from and at an angle to the attaching stud and provided with a notched angular lug located parallel to the attaching stud to support a straight rod, said bracket having a notch to receive the pindle of a shade roller.

3. A curtain bracket of the character described formed of a single sheet of metal of substantially S-shape having its forward upper end slit, the upper edge thereof being rolled to form a horizontal attaching stud for a bow-end rod, the portion beneath the slit being bent laterally and at an angle and provided with a notched angular ear located parallel to the attaching stud to support a straight rod, the lower portion of the bracket having a notch to receive the pindle of a shade roller.

In testimony that I claim the above, I have hereunto subscribed my name.

LLOYD SYKES.
